(57) **CLAIM**

The ornamental design for a wheel or wheel cover, as shown and described.

DESCRIPTION

This application contains subject matter related to the following co-pending U.S. design patent application:
 Application Ser. No. 29/741,672, filed herewith and entitled "Wheel or Wheel Cover".

FIG. 1 is a perspective view of a wheel or wheel cover according to the design; and,

FIG. 2 is a front view thereof.

In the drawings, the broken lines depict portions of the wheel or wheel cover and form no part of the claimed design. Also enclosed is a set of photographs of an embodiment of the design.

1 Claim, 2 Drawing Sheets

FIG. 1

FIG. 2
